Primary Examiner—Ruth McInroy*(74) Attorney, Agent, or Firm*—Brinks Hofer Gilson & Lione(57) **CLAIM**

I claim the ornamental design for a vacuum cleaner handle, as shown and described.

DESCRIPTION

FIG. 1 is a side perspective view of a vacuum cleaner handle of the present invention;

FIG. 2 is a front elevation view thereof;

FIG. 3 is a rear elevation view thereof;

FIG. 4 is a top view thereof;

FIG. 5 is a bottom view thereof;

FIG. 6 is a first side view thereof, the second side view being a mirror image thereof; and,

FIG. 7 is a cross-section view taken along the line 7-7 of FIG. 5.
